DESIGN FOR A COMBINED CHRISTMAS TREE LIGHTING SET AND CASE THEREFOR OR SIMILAR ARTICLE

Leopold Pollock, New York, N. Y.

Application September 6, 1934, Serial No. 53,216

Term of patent 3½ years

To all whom it may concern:

Be it known that Leopold Pollock, a citizen of the United States, and resident of New York city, in the county of New York and State of New York, has invented a new, original, and ornamental Design for a Combined Christmas Tree Lighting Set and Case Therefor or Similar Article, of which the following is a specification, reference being had to the accompanying drawing forming part thereof, in which,

The figure is a perspective view of a combined

Christmas tree lighting set and a case therefor embodying my design.

In the drawing A designates a case and B a sheet member lying in the bottom of the case and having integral tabs C supporting the lamps.

I claim:

The ornamental design for a combined Christmas tree lighting set and case therefor, or similar article, substantially as shown and described.

Dated, New York city, N. Y., August 25th, 1934.

LEOPOLD POLLOCK.
